UNITED STATES PATENT OFFICE.

ELMER M. JONES, OF ATLANTA, GEORGIA, ASSIGNOR TO JONES SIGNAL SYSTEM COMPANY, OF ATLANTA, GEORGIA, A CORPORATION OF GEORGIA.

MOVABLE CONTACT MEMBER.

1,109,587.

Specification of Letters Patent.

Patented Sept. 1, 1914.

Application filed July 7, 1909. Serial No. 506,277.

To all whom it may concern:

Be it known that I, ELMER M. JONES, a citizen of the United States, residing at Atlanta, in the county of Fulton and State 5 of Georgia, have invented a certain new and useful Improvement in Movable Contact Members, of which the following is a full, clear, and exact description, reference being had to the accompanying drawings.

10 This invention relates to an electric signal system wherein it is desired to have a variably positioned member along the track way cooperating with a moving vehicle.

15 My device is well adapted for use in connection with a cab signal system, employing home or distant ramps, which are movable into and out of position to coöperate with a movable member of an indication controller or air brake mechanism on a locomotive or 20 car.

The present invention provides, in a very simple and efficient form, for such a disappearing ramp, with electrically controlled mechanism for effectively moving it. In its 25 preferred form the ramp normally stands in a danger position, and is moved to a safety position by an electric actuation.

Among the objects of my invention is the provision of very effective mechanism for 30 moving the contact member or ramp; for preventing its movement except in response to the electrical actuation and until the conditions of the circuit change; for automatically cleaning the surface of the ramp when 35 actuated, and for automatically operating a visible signal when the ramp is moved.

The drawings clearly disclose my invention embodied in the mechanism for moving a member in the form of a ramp laterally consequent upon an electric actuation.

40 Figure 1 is a cross section through such mechanism; Fig. 2 is a plan of the mechanism; Fig. 3 is a side elevation looking toward the ramp; and Fig. 4 is a view of the visible signal mechanism.

45 As shown in the drawings, 1 indicates a casing or frame of the device, which is a long box-like member preferably a single integral casing.

50 2 indicates a removable door for the back and upper side of the casing, this door being shown as held in place by a fork 3 at the upper end and a hasp 4 carried by the casing near the lower end of the back and 55 projecting through the door and adapted to receive a padlock.

The ramp designated 5, consists of a comparatively long block, pivoted near its lower edge by means of gudgeons 6. This ramp, when in the extended position, has a substantially horizontal surface 7, the end portions of which are inclined downwardly. The mechanism about to be described operates to swing the ramp toward the casing to carry it out of the path of some coöperating 60 member on the vehicle.

To cause the inward movement of the ramp under electric control, I provide the following mechanism: 20 indicates a motor, on the armature shaft 21 of which is a worm 22. This worm meshes with a worm wheel 23, on the shaft of which is a sprocket wheel 25. Running on this sprocket wheel and on another sprocket wheel 26 is a sprocket chain 27 having pins 28 projecting at the 70 link joints. Pivoted to the ramp at 30 is an arm 31, the other end of which carries a latch lever 32. This lever has a bifurcated lower end 34 which may straddle the chain and stand in the path of the pins 28 or just 75 above their path according to the position of the latch lever. The latch lever is acted upon by a light spring 40 tending to keep it elevated and by a magnet 42, which coöperates with an armature 43 on the lever, the 80 magnet being mounted on the bracket 44 secured on the arm 31.

The magnet and the motor are on branches of the same electric circuit. When this circuit is closed the motor begins to 85 rotate and the chain travels in the direction of its upper reach away from the ramp. Immediately the pins 28 engage the forked end of the latch lever and move the arm and ramp inwardly. This movement continues until the latch lever passes between the two projecting jaws 50 of a latch 90 adapted to hold the lever.

On the inner face of the ramp is a projecting lug 55, which, as the ramp comes to 100 its innermost position, is adapted to engage the lower one of a pair of contact strips 57 and separate them. These strips form a portion of the circuit to the motor so that when the lug causes this separation the circuit of 105 the motor is broken and the driving action stops. Accordingly, the ramp is left standing in its innermost or safety position so long as the current continues to flow through the magnet, the magnet holding the latch 110 in operative position.

When the current through the magnet is

interrupted the outward pull on the arm caused by the overhanging weight of the ramp swings the latch lever downwardly away from the magnet, thus releasing the 5 toe of the latch lever from the stationary latch and allowing the ramp to return by gravity to normal position.

The electric circuit to cause the above operation is very simple and may consist of 10 two main lines *a* and *b*, each of which respectively branch into lines *a'* and *a''*, and *b'* and *b''*. The lines *a'* and *b'* are terminals of the magnet 42, while the lines *a''* and *b''* pass to the terminals of the motor, as indicated 15 by the binding posts 63 and 64. The line *b''* is broken at the contact strips 57, heretofore referred to, these strips normally contacting with each other and constituting terminals of the two portions of this line *b''*. 20 The visible signal is suitably connected with the ramp, as shown in Figs. 3 and 4, and may comprise a blade 70 pivoted at 71 and connected by a link 72 with a bell crank 73 which is connected by a link 74 with an 25 ear 75 on the inner face of the ramp. When the ramp is in its outermost position, the blade is horizontal or at danger. When the ramp is drawn inward to safety position, the blade swings downwardly to a more or less 30 vertical position, which represents safety, as will be well understood.

To prevent the formation of ice on the upper surface of the ramp or the collection of snow or dirt thereon, I provide a cleaning 35 member 80 which is in the form of a plate hinged to the casing at 81 and having its outer and lower edge 82 resting on the upper surface of the ramp. During the inward movement of the ramp, this engaging edge 40 of the plate travels relatively outwardly along the ramp shoving off any snow, ice, dirt or other accumulation thereon. The cleaning member is provided with a downwardly extending lug 85 which in the normal 45 position of the parts stands behind the lug 55 on the ramp and prevents any accidental or surreptitious raising of the cleaner. Accidental inward movement of the ramp is prevented by the pins 28 which would be hit 50 by the back side of the lower end 34 of the latch lever.

It will be seen from the above description that my mechanism is simple in construction, that there is nothing about it to get out of order, and that it is not adapted to be injuriously effected by snow or ice. The gearing provided is very powerful, so that a ramp of considerable weight may be effectively moved by an electric current of ordinary strength. The ramp responds immediately to the circuit change, moving from a normal danger position to a safety position

and there remaining so long as the circuit condition continues, returning automatically to the danger position when this condition 65 is interrupted.

Having thus described my invention, what I claim is:

1. The combination of a casing adapted to be secured along a trackway, a member 70 parallel with the track and pivoted to the casing having an exposed contact surface, arms for moving said member transversely into the casing, a motor, mechanism driven thereby, and controllable means for connecting said arms with said mechanism.

2. The combination of a contact member mounted alongside of the trackway and substantially parallel thereto and having an exposed upper surface parallel with the track, 80 means for moving said contact member, and means for automatically scraping across its surface consequent upon such movement.

3. The combination of a casing adapted to be secured along a trackway, a movable 85 contact member parallel with the trackway and carried by the casing, means for moving it transversely into the casing, and a cleaning plate extending longitudinally of the contact member and carried by the casing, 90 for scraping across the surface of the contact member by resting against it, whereby said cleaning plate moves relatively along the surface of the contact member.

4. The combination of a movable contact 95 member having a normally upwardly facing surface, means for moving such member, a cleaning device adapted to rest on the surface and scrape across it as the contact member moves, and means for normally locking 100 the cleaning device against movement.

5. The combination of a casing extending lengthwise of a trackway, a movable contact member extending lengthwise of and pivoted to the casing, a motor, gearing driven 105 by the motor and including a sprocket chain, arm connected with said contact member, and a magnetically controlled latch on the arm for connecting the arm with the sprocket chain, whereby the contact member 110 is moved into the casing transversely.

6. The combination of a longitudinal casing extending lengthwise of a trackway, a movable ramp extending lengthwise of and pivoted to the casing and adapted to close 115 an opening in one side of the casing, and means for moving the ramp transversely into the casing.

In testimony whereof, I hereunto affix my signature in the presence of two witnesses.

ELMER M. JONES.
